UNITED STATES PATENT OFFICE.

JAY C. LATHROP, OF CINCINNATI, OHIO, ASSIGNOR TO LATHROP-HOGE GYPSUM CONSTRUCTION COMPANY, OF CINCINNATI, OHIO, A PARTNERSHIP COMPOSED OF JAY C. LATHROP AND EDWARD CLYDE HOGE.

STRUCTURAL ROOF AND FLOOR.

Application filed February 23, 1927. Serial No. 170,237.

My invention relates to structural roofs in particular, and has to do with the forming of strong, light and durable roofs for buildings, more especially flat roofed buildings, 5 with the minimum of labor on the job, the whole being built so far as possible of prepared materials, combined in a simple way to fulfill all of the necessary requisites.

It has been the general plan of construction in the building of structural roofs in the past to proceed along one of several distinct lines. One line was to construct a metal framework for the roof, forming a series of hollow box-like compartments, use false work 15 or permanent bottom boards of plaster, stretch or loop reinforcing fabric over the whole construction and fill same with a poured slab of cement, plaster or the like. Another line has been to use a structural 20 framework or deck, and lay on it, in some suitable way, preformed slabs of reinforced plaster, which were molded with reinforcing wire within them. Another way has been to use removable false work for retaining the 25 roof slab instead of plaster boards.

My present plan is to do neither of these things, and I depart entirely from reinforced work, whether preformed or formed on the job, and instead I employ the box-like structure of the poured job, such as for example 30 as is shown in the patent of my associate, Edward Clyde Hoge, U. S. Patent No. 1,464,711, dated August 14, 1923. Into the series of box-like compartments I lay members which rest upon the flanges of the trans- 35 verse rails or beams, and are stiff enough and strong enough, dependent upon the spacing given them, to transfer any load which the roof is called upon to sustain to the rails or 40 beams. I then fill in between or about the form work with preformed light boards of plaster, fibrous structure, or other accepted insulating material, either preformed or 45 poured as a slab or coating, so as to leave a substantial level top to the structure, and over the whole I lay an imperforate roof deck of tar and gravel, saturated fabric in built up layers or whatever type of top surface is required.

50 Thus I take advantage of the framework structure of the poured on the job roofs of the Hoge patent type, to supply the load sustaining element, and in building up my roof deck, I use among other parts of the pre-

formed filling pieces, sheets of corrugated 55 metal, or other stiff and durable sheet or slab means, which will be closely enough supported due to the spacing of the framework, to transmit the loads to be supported to the said framework without the necessity of employing any reinforced cement construction.

I accomplish my objects by that certain construction and arrangement of parts of which an example will be specifically illustrated and described, and the invention inherent therein will be set forth in the claims 65 that follow.

In the drawings:

Figure 1 is a section taken across the roof structure parallel with the supporting beams. 70

Figure 2 is a section taken at right angles to Figure 1.

Figure 3 is a perspective of a typical metal sheet as used by me.

It will be understood that I have illustrated 75 only one type of construction, the essentials of which constitute an example of my invention. Thus I have shown the beams 1, which may be channels instead of I-beams, which beams are set in the walls or carried on 80 trusses of a structure, and form the main support for the roof. Across these beams I lay the transverse elements of the roof frame, which consists of flanged members, such as rails 2, or angle bars set together to present 85 the lateral base flanges as in a rail. The spacing of these rails is quite close, and is arranged in accordance with the strength of the filling structures.

If it is desired to have a plaster board 90 under face to the roof, and this is becoming quite popular, I will first lay across between the rails, and resting on the flanges thereof, the plaster boards 2a. These boards are not of sufficient strength to transfer a load from 95 above to the rails and beams. In order to accomplish this function of the roof, I employ some stiff sheets or plates or boards, which should be as light in weight as possible. An effective device for this purpose is 100 corrugated sheet metal, with the corrugations running in the direction that the load is to be transferred. Thus if the rails are spaced on 24 inch centers, the sheet metal will be say 23 inches wide, corrugated transversely to the direction of the rails, and as long as convenient. I have indicated the 105 sheet metal at 3, and it will be convenient to

have the depth of the sheet metal corrugations such as to fill the space between the rails, up to the bottom of the balls of the rails.

- 5 To fill in the structure up to the tops or above the tops of the rails, thus facilitating the superimposition of the usual roof top surface, I may use pieces of preformed plaster in slabs 6, or preformed slabs of bagasse pulp, 10 or the like, the object being a filling which will not readily dent, and which will fill up the structure to an even top with the rails, with an additional layer above rails if required for insulation.
- 15 I then apply tar and gravel, layers of saturated felt and asphalt, or any other kind of a roof top surface, as indicated generally at 4.

Where the plaster board is omitted beneath the sheet metal, the sheet metal will show at the under side of the roof, but in any event, the side edges of the sheet metal or other strong and light slab or strip will rest on the flanges of the rails, and cover the 25 space between them.

The plaster board will usually be equipped with battens, as at 5, which will be arranged to fit under corrugations of the metal, and the top layer of board can be nailed through 30 the sheet metal into the battens. Also the sheet metal can be nailed to the battens. Also instead of battens, strips of the wood can be laid across between rails and riveted or tied in some way to the sheet metal to 35 provide a body to receive nails for both top and under surfacing.

However, in my construction there is no 40 poured slab and reinforcement, in which the rail webs are embedded, or which the rails serve to reinforce to any degree, although a 45 poured plaster top to the structure may be employed where it is desired to make it thicker. Also, the pieces 6 may be poured instead of preformed, the latter being preferred for economy.

I rely upon a structural frame and a structural filling with load transferring devices 50 forming part of the filling, so as to provide a roof which is cheap to build and strong and durable in use, using the transverse metal bars, rails or the like, to do the work of

housing the filling structures, which in part are strong enough to take care of transferring such loads as are applied to the rails. When corrugated sheet metal is used with 55 filling plates on the top and bottom, the corrugations form insulating air spaces, which is a decided advantage in my roofs.

Having thus described my invention, what I claim as new and desire to secure by Letters Patent, is:—

1. A roof formed of main supporting beams, transverse flanged rails or the like, laid across the beams and supported thereby, said rails being laid to spaced centers to accommodate the functions of the filling structure, and preformed filling bodies resting upon the flanges of the rails and forming bodies extending up to the tops of the rails and comprising bottom facing plates of plaster board or the like, corrugated sheet metal having corrugations of a depth to fill the space between the rails up to the balls thereof, filling pieces laid on top of the sheet metal so as to fill the spaces between the rails to 75 a level body, and an imperforate roof deck over all, to exclude the weather, as and for the purpose described.

2. In a roof, the combination with supporting beams, of transverse supporting 80 members arranged across the beams, and having flanges at their bases, and forming side walls of spaces to be filled in forming the roof, and preformed bodies laid into said spaces, resting upon the flanges so as to substantially fill said spaces, said bodies comprising stiff elements formed of corrugated sheet metal having inherent strength sufficient to transfer the roof load imposed thereon to the transverse supporting members and 90 having its corrugations extending in the direction of transference, said members being spaced with relation to the strength of said stiff elements, thus permitting said transference to take place, and an insulating body 95 imposed upon said preformed bodies and filling the spaces between said transverse members, said insulating bodies being of sufficient strength to transmit direct load to the preformed bodies, but of insufficient compressive value to serve as a reinforced slab.

JAY C. LATHROP.
